MEMO HOLDER

Norbert Leopoldi, 4180 Marine Drive,
Chicago, Ill. 60613

Filed June 19, 1972, Ser. No. 263,958

Term of patent 14 years

Int. Cl. D19—02

U.S. Cl. D74—2 B

FIG. 1 is a front perspective view of a memo holder showing my new design;

FIG. 2 is a rear elevational view;

FIG. 3 is an enlarged scale right side elevational view partly in vertical section taken substantially on line 3—3 of FIG. 2, an intermediate portion of the vertical member being broken away for ease of illustration; and

FIG. 4 is an enlarged scale horizontal sectional view taken on line 4—4 of FIG. 3, the base portion being omitted for ease of illustration.

I claim:

The ornamental design for a memo holder, substantially as shown and described.
